THERMOSTATIC GENERATOR

Walter C. Lindemann, Carl J. Weis, and Adolph T. Schmidt, Milwaukee, Wis., assignors to A. J. Lindemann & Hoverson Company, Milwaukee, Wis., a corporation of Wisconsin

Application February 20, 1931, Serial No. 517,240

12 Claims. (Cl. 158—42.4)

The present improvements relates, in general, to hydrocarbon stoves and more particularly to burners and generators therefor and to improve means for automatically controlling the fuel supply leading thereto.

A primary object, among others, is to provide an automatic control means for the fuel supplied to a vapor generator and burner, and one which is foolproof in operation and embodies features of safety and reliability.

A further object is to provide an improved generator construction combining into a compact structure an expandable and a non-expandable member which cooperate in controlling the operation of valve means for regulating the fuel supply. Another object of the improvements is to provide a device of the foregoing type, wherein vaporization of the fuel is facilitated.

A novel type of adjustable fuel inlet is also provided and constitutes a further object of the improvements. Various other objects and advantages of the improvements will be apparent to those skilled in the art upon reference to the accompanying specification and drawing, in which—

Fig. 1 is a side view of a burner and vapor generator embodying one form of the present improvements, certain parts being in section, others in elevation;

Fig. 2 is an enlarged sectional view of the fuel inlet end of the improvements.

Referring to the drawing, the burner 5 has the generator 6 disposed thereover and receives vaporized fuel from the outlet end of the generator 35 through conduit 7. As is customary, a certain amount of air enters the pipe 7 at the point where it receives the vapor from the generator, so that a suitable mixture is conveyed to the burner for consumption. It is understood that the burner 40 5 may be one of a plurality of service burners, all of which may receive vaporized fuel from the generator 6, or each such burner may have an individual generator for providing the fuel supply.

As more clearly seen upon reference to Fig. 2, the generator casting 8 is suitably bored and threaded to accommodate parts of the valve structure. A liquid fuel supply pipe (not shown) is attached to nipple 9 which has a conduit 10 leading into a bore of the casting where it communicates with an annular channel 11 provided between adjustable collar 12 and the wall of the bore. A port 13, extending through the collar, communicates with a peripheral groove 14 provided on the adjustable stem 15. As illustrated,

this stem 15 has screw threaded engagement with the casting 8 and has a centrally disposed channel 16 which communicates with groove 14 through radial port 17.

The exposed end of channel 16 forms a valve seat 18 with which the valve plug 19 cooperates. A longitudinal channel 20 in said plug affords communication between the valve seat chamber 21 and the interior of the generator. Accordingly a liquid fuel inlet to the generator is thus afforded when valve 19 is unseated, while communication to the generator is cut off when said valve is closed.

Suitable packing means 22 are provided at either end of collar 12 and provide an effective seal between the collar, stem 15 and casting 8. A ring 23 and bushing 24 surround stem 15 and may be suitably adjusted for tightening the packing 22, during which operation the collar 12 may be shifted to and from its illustrated position. Likewise the stem 15 may be adjusted by reason of its screw threaded mounting. It is notable that in the assembly of these parts or in the adjustment thereof, communication through collar 12 and stem 15 is afforded regardless of the position in which these elements come to rest after assembly or adjustment is accomplished.

The tubular generator 6 is communicably attached to the casting 8, projects therefrom over the burner 5, and terminates in the usual bushing 25 and outlet member 26. A valve stem 27, having valve 28, has screw threaded engagement with bushing 25, whereby discharge through the outlet may be controlled by advancing or retracting the valve and stem. The inner end of bushing 25 is counter bored and screw threaded for receiving the threaded end of a valve actuating member 30. In the present embodiment this member is in the form of a tubular sleeve surrounding stem 27 and disposed between it and the generator tube 6. As illustrated, the tubular members 6 and 30 are spaced for providing an annular channel or passageway 31 which extends from the juncture of the generator, sleeve and bushing 25 to the inlet end of the generator. Ports 32 in sleeve 30 afford communication between channel 31 and the space 36 between stem 27 and the sleeve 30, which in turn communicates with the outlet of the generator through groove 33 in stem 27.

While the generator 6 and sleeve 30 are secured to each other at one end by means of bushing 25, the other end of the sleeve is free and has no connection with the generator or casing 8. As illustrated, the free end of the sleeve is flared at 35 and engages the valve plug 19. In this manner

105
110

the flared end assists in maintaining the sleeve 30 in spaced relation to the generator, so that an annular channel 31 will have free communication with the channel 20 in valve plug 19.

5 The generator 6 and sleeve 30 are made of metals which have different coefficients of expansion, that is, the expansion of the generator 6 is greater than that of the tube or sleeve 30. For example, the tube 6 may be made of steel and tube 30 may be made of invar metal, or if desired, the outer tube may be of brass and the inner tube of steel. Any other metals may be employed for the tubes, so long as the difference in expansion is sufficient to permit opening of valve plug 19, as 10 hereinafter described.

When the generator is ready for operation, gasoline or other fluid fuel under pressure obtains in passage 10 and the communicating channels up to valve seat 18. In the illustrated embodiment, 20 the generator is cold, so that the tube 6 is contracted, and tube 30 is in its normal position engaging valve 19 and holding it tightly against seat 18, so that no fuel can pass to the generator. The valve 28 may now be retracted and the generator 25 preheated by any suitable priming means. This preliminary heating causes generator tube 6 to expand and thereby withdraw the substantially non-expansible tube 30, so that its flared end 35 is not exerting a closing force on valve plug 19. 30 Since this valve is loosely mounted, the pressure of the fuel in channel 16 forces the valve open and the liquid fuel passes through channel 20 in the valve and flows into annular channel 31 between tubes 6 and 30. While some of the fuel 35 may flow into the space 36 between the stem 27 and tube 30, the greater portion thereof will enter channel 31 which is larger than the aforementioned space. A thin film of fuel is thus provided in the annular channels so that vaporization 40 thereof is facilitated by the heat applied to the generator. The vaporized fuel then passes through ports 32 into the space 36, whence it passes through groove 33 in valve stem 27 and thence through the outlet 26 to the conduit 7 and 45 on to burner 5 which may now be ignited. The heat of the main burner now maintains the generator in operation, with tube 6 expanded and valve 19 open. So long as the burner is thus operating, the flow of fuel and the vaporization 50 thereof will continue.

In the event that burner 5 is inadvertently extinguished, the generator 6 cools and contracts, carrying tube 30 back with it, while the flared end 35 of the latter forces valve 19 home to its seat, thereby automatically shutting off the supply of fuel to the generator. In this cool condition of the parts, the valve is held tightly closed by the engagement of tube 30 therewith, so that no fuel can escape, regardless of the position of 60 valve 28.

It is notable that the thin film of fuel obtaining between stem 27 and tube 30 is likewise readily vaporized and exudes through the outlet along with the major portion of the vaporized fuel.

65 The simplicity of the improvements cannot be over emphasized. In employing the tubular member 30 for controlling the inlet valve, accurate alignment of parts is assured and all danger of warpage due to the use of a rod is eliminated. 70 Since tube 30 has a free or floating end, it has freedom of operation and cannot bind, stick, or be hampered in its movement, as might be the case were it mounted for sliding movement in a bushing of some sort. Furthermore, the fact that tube 30 is independent of and not connected to

valve 19, provides more positive operation and prevents an excess of heat being communicated to the valve, whereby the latter is more readily movable.

80 The novel inlet construction, including adjustable elements 12 and 15, is advantageous due to its simplicity and adjustability. As aforementioned, these parts may be assembled and adjusted at the factory and will insure communication with passage 10, regardless of their position within a given range. The elements of the present improvements are so well aligned, that the structure may operate indefinitely and the generator structure removed and replaced many times without the necessity of altering or adjusting stem 15. This capability of insuring proper adjustment at the time of assembly at the factory, is of marked importance.

85 Various modifications of the present improvements may occur to those skilled in the art and may be made without departing from the scope and purview of the invention.

90 We claim:

1. The combination with a vapor burner, of a vapor generator comprising nested tubes of different coefficient of expansion, a valve controlling discharge of fuel from said tubes, valve actuating means therefor disposed within said tubes, a valve controlling admission of fuel to said tubes, one of said tubes engaging said last named valve for 100 influencing its movements in response to thermal conditions of said generator.

2. The combination with a vapor burner, of a vapor generator comprising inner and outer tubes connected at one end for providing an annular chamber therebetween, a valve controlling discharge of fuel from said chamber, valve actuating means therefor disposed within said tubes, a fuel inlet for said chamber, a loosely mounted valve controlling same, said inner tube engaging said 110 last named valve and being of less coefficient of expansion than said outer tube whereby movement of the latter in response to thermal conditions influences operation of said last named valve.

115 3. A vapor generator comprising a tubular member having a fuel inlet and a fuel outlet, valves controlling said inlet and outlet, a manually operated rod extending along the interior of said member for actuating said outlet valve, means 120 operatively associated with said member for holding said inlet valve closed, said means being movable relative to said inlet valve upon expansion of said tubular member, said inlet valve being free to be opened by the fuel pressure in said 125 inlet.

130 4. A vapor generator comprising a thermally responsive tubular member having a fuel inlet and outlet, a valve and valve actuating means for said outlet extending throughout said member, a sleeve 135 within and operatively connected with said member for movement therewith, a freely slid able valve controlling said inlet, said sleeve engaging said valve for closing same, said valve being freely slid able upon withdrawal of said sleeve.

140 5. A vapor generator comprising a thermally responsive tubular member having a fuel inlet and outlet, a valve and valve actuating means for said outlet extending throughout said member, a sleeve operatively associated with said generator for 145 movement therewith and disposed within same, a valve controlling said inlet, said valve and sleeve being mounted independently of each other but cooperatively positioned whereby movement of the sleeve in one direction closes said valve and 150

- movement in an opposite direction imparts no movement to said valve.
6. A vapor generator comprising a thermally responsive tubular member, a manually operated valve for controlling the flow of fuel from said member, a valve rod for said valve disposed within said member, a loosely mounted valve controlling the flow of fuel to said member, a sleeve surrounding said rod and fixed to said member and engageable with said loosely mounted valve for closing same upon contraction of said member.
10. A vapor generator comprising a thermally responsive tubular member, a substantially non-expansive member fixed thereto, a fuel inlet for said tubular member, a fuel outlet for said member, valve means extending throughout said member for controlling said outlet, and a valve in the path of travel of said non-expansive member but detached from said members, said valve being moved in closing direction by said non-expansive member and being moved in opening direction by means other than said non-expansive member.
15. A vapor generator comprising a thermodynamic tube having an inlet for fuel under pressure, an outlet for said tube, a valve for said outlet, a valve stem within said tube, a freely movable valve disposed across said inlet adapted to be opened by the fuel pressure, a member independent of but normally engaging said last named valve for resisting said opening movement, said member being operatively connected with said tube, whereby upon expansion of the latter said member is retracted from said last named valve so that the valve is free to be moved independently of said member.
20. A vapor generator comprising a thermostatic tube having an inlet for fuel under pressure, an outlet for said fuel, a valve and valve stem for said outlet, a freely movable valve disposed across said inlet adapted to be opened by the fuel pressure, a sleeve surrounding said valve stem responsive to movements of said tube normally engaging said valve for resisting said opening movement, said valve being mounted independently of said sleeve, the expansion of said tube causing retraction of said sleeve whereby the valve is free to open under fuel pressure and the contraction of said tube causes movement of said sleeve for closing said valve.
25. A vapor generator comprising a thermodynamic tube having an inlet and an outlet, a valve stem disposed in said tube, a sleeve between said tube and stem and connected to the former, a loosely mounted valve controlling said inlet and adapted to be opened by the fuel pressure therein, said sleeve normally holding said valve closed but being retractable therefrom upon expansion of said tube.
30. A vapor generator comprising a thermodynamic tube having an inlet and an outlet, a valve and valve rod disposed within said tube for controlling said outlet, a tubular member between said rod and tube and having one end thereof connected to said tube, the other end of said tubular member projecting toward said inlet, a valve for said inlet engageable by said tubular member for closing same, said tubular member being movable to and from said valve in response to expansion and contraction of said tube.
35. A vapor generator comprising nested tubular members of different coefficients of expansion having a fuel inlet and a fuel outlet, a valve and valve rod disposed within said tubular members for controlling said outlet, a second valve controlling admission of fuel to said tubular members, one of said tubular members engaging said second valve for influencing its movements in response to thermal conditions of said generator.
